UNITED STATES PATENT OFFICE.

WILLIAM P. THOMSON, OF NEW YORK, N. Y., ASSIGNEE TO THE RAIL JOINT COMPANY,
A CORPORATION OF NEW YORK.

CANTED RAIL-JOINT.

1,263,818.

Specification of Letters Patent. Patented Apr. 23, 1918.

Application filed March 7, 1918. Serial No. 221,607.

To all whom it may concern:

Be it known that I, WILLIAM P. THOMSON, citizen of the United States, residing at New York, in the county of New York and State of New York, have invented certain new and useful Improvements in Canted Rail-Joints, of which the following is a specification.

This invention relates to a novel canted rail joint for use on tangents as well as curved sections of track.

To this end the invention has in view a novel construction of splice bar possessing special utility as a support for maintaining the rails in a canted or inclined position, and having the several members thereof so designed and related as to effectually absorb and distribute the loading strains. In that connection, it is proposed to utilize the desirable and characteristic features of the continuous type of joint bar in a construction which provides a substantial and rigid base support for the rails while at the same time so distributing the lateral thrust of the wheel loads as to firmly maintain the position of the rail and allow the latter to adjust itself easily under the load.

Accordingly, an important and distinctive object of the invention is to provide a joint bar having the flexibility as well as relative rigidity of a continuous type of bar, and which is so designed that it will rigidly support and hold the rail in an inclined or canted position while at the same time permitting the ties to be bedded in their usual horizontal position.

With the above and other objects in view which will more readily appear as the nature of the invention is better understood, the same consists in the novel construction, combination and arrangement of parts hereinafter more fully described, illustrated and claimed.

A preferred and practical embodiment of the invention is illustrated in the accompanying drawings, in which:

Figure 1 is a general diagrammatic view illustrating by dotted lines the normal position of a rail upon the tie, and showing in full lines how, as a result of the combined forces acting on the head of the rail, the same is usually caused to tilt outwardly and embed its outer flange in the tie.

Fig. 2 is a view of the improved rail joint showing in full lines how the present inven-

tion proposes to support and maintain the rail in an inwardly canted position to obviate the defect shown in full lines in Fig. 1.

Fig. 3 is an enlarged end view of a rail joint showing a joint bar including the present improved features for supporting a rail in a canted position.

Figs. 4 and 5 are views graphically illustrating the practical method of manufacturing both bars of the joint from the same rolls.

Similar reference characters designate the corresponding parts throughout the several figures of the drawings.

As is well known to those familiar with track conditions, there is a decided tendency of rails in either straight or curved sections of track to "roll out" or become tilted outwardly due to the combination of forces acting upon the head of the rail, thus causing undesirable disalignment and spreading of the rails. That is to say, owing to the wheel load acting vertically and the wheel flange thrust acting horizontally on the head of the rail, there is a tendency for the head of the rail to cant outwardly from the gage side. Under the most favorable conditions of track, rolling stock, and speed, there would be very little wheel flange thrust against the rail. And, if curves could be elevated to meet the requirements of each train, if car trucks pivoted freely, and the track could be maintained to a perfect line and surface, the lateral thrust or strain on the rails would be negligible. However, since these ideal conditions are not entirely practicable, the lateral wheel flange thrust becomes a factor that must be taken care of thus making it desirable to cant or tip the rails inwardly so as to bring the rail base in a plane approximately at right angles to the resultant of the combined vertical and lateral forces acting on the rail.

To illustrate the conditions above referred to, reference may be made to Fig. 1 of the drawings, which shows a rail in dotted lines seated on a tie according to the conventional practice. In this illustration the vertical center line of the rail is normally perpendicular and at right angles to the supporting surface of the tie, and the full lines show the position the rail will take, after being in service some time, due to the resultant force of wheel load and flange thrust which tends to place greater

pressure on the outer flange portion of the rail base than on the inner flange portion of the rail base thus causing the former to become embedded in the tie, and tilting the rail outwardly and downwardly from its proper seating plane. To further illustrate these conditions the dotted line $a-b$ represents the load of, or the downward force of, the wheel, the direction of this force being vertical to the center of the rail as originally applied to the tie, or in a plane parallel thereto, the line $b-b$ represents the lateral thrust of the wheel flange and c the diagonal line in the force parallelogram $a-b-b'$, represents the resultant of the two above forces acting upon the rail which causes it to "cant" in the manner referred to.

Accordingly, as will be observed from the full line position of the rail shown in Fig. 2, it is proposed to provide a rail joint which will cant or tilt the rail inwardly so that its vertical axis is disposed in a plane coincident to or parallel with the resultant force c , and hence the base of the rail will be maintained normal to that force c . This is effectively provided for in the present invention by means of the novel formation of the base flanges of the joint bars, whose upper rail supporting surfaces are disposed at right angles to the resultant of the applied forces, so that in supporting the rail, in this way, uniform pressure is distributed throughout the entire tie bearing surfaces of the rail joint and the tendency of the rail to "roll out" is eliminated.

As previously indicated it is contemplated to adapt the features of the well-known continuous type of joint bar to a bar for supporting a rail in a canted position. To embody these novel features in a joint bar it is proposed to provide the bars A and B each essentially including an upstanding web portion 1 having a head 2 for engaging the underside of the head of the rail R, a foot flange 3 for engaging the upper side of the rail flange, and a substantially horizontal integral rail supporting base member 4 which underlies and supports the bases of the rails. As will be observed from the drawings, these rail supporting base members of the bars A and B are provided with the laterally inclined or oblique rail seating surfaces 6 and 7 respectively, while the vertical axes $x-x$ of the upstanding web portions 1 thereof lie parallel to the vertical center $y-y$ of the rail R and at right angles to the seating surfaces 6 and 7, thereby assuming an inclined or canted position.

From the foregoing description it will now be observed that a distinctive and practical feature of the invention is that of a splice bar having a canted rail seat carried by a bolting member which is engaged by the joint bolts. That is to say, the present

invention involves the features of tying a rail supporting seat, canted at a definite angle, up to the joint bolts of the joint, thereby obtaining the advantageous results herein explained and pointed out. And, it will also be apparent that a further distinctive feature is the utilization of the principles and characteristic features of the continuous type of rail joint bar, in a bar especially designed for supporting a canted rail. Furthermore, the present type of joint provides for more effectively distributing the wheel loads over and upon the ties through the engagement of the inclined upstanding web portions of the joint bars with the under side of the rail head and upper side of the base flange of the rail.

It is preferable in carrying forward the present invention, to manufacture the improved joint bar by a rolling mill process. In this connection, a practical method which may be advantageously employed for making these bars is illustrated by the diagrammatic view, Figs. 4 and 5 of the drawings. As shown therein, the two bars of the joint, embodying the present invention, may be manufactured by the same rolls, and thereby obviate the necessity of making bars up in rights and lefts. That is to say, according to the novel plan illustrated it will be observed that the passes of the rolls can be so designed as to produce a bar section formed with a longitudinally divided base comprising separate base flanges x and y , respectively of different widths and rolled "open" in the manner of the process of rolling rail joint bars of the continuous type. The said base flanges " x " and " y ," when the bar is delivered from the final pass of the rolls, are disposed in a widely separated relation, the flange " x " being innermost and the flange " y " being outermost. So, in producing the bar for the inner or gage side of the joint it will only be necessary to bull-doze or bend the innermost base flange " x " into rail seating position, and to shear the entire bottom part of the bar on a diagonal line, as indicated by the line "S-S," which will eliminate the outer base flange " y " and provide the flat tie-seating surface of the bar. To produce the outer joint bar, it is only necessary to bull-doze or bend both the inner and outer base flanges " $x-y$ " upwardly into matching relation to obtain the proper formation for the base of the bar, and in this operation, the outer flange " y " will present at the bottom the tie seating surface for the bar.

While the method of manufacture described is a practical way of making the improved joint bars in an economical manner, it will of course be understood that other processes may be resorted to and it will also be understood that change in the form, proportion and minor details of construction

may be resorted to without departing from the spirit of the invention or scope of the appended claims.

I claim:—

5. 1. A rail joint including the combination with the rails and the joint bolts, of a splice bar having a bolting member engaged by the joint bolts and carrying a base member provided with a canted rail supporting seat.
10. 2. A rail joint including the combination with the rail and joint bolts, of a splice bar having a canted seat held in supporting engagement with the rail bottom by the joint bolts.
15. 3. A splice bar for canted rails having a base member provided with an upper inclined rail seating surface, and a lower substantially horizontal tie-engaging surface.
20. 4. A splice bar for canted rails having an upright canted web member and a base member provided with an inclined rail seating surface and a substantially horizontal tie-engaging surface.
25. 5. A rail joint for canted rails including in combination with the rails, splice bars having rail supporting bases provided with laterally inclined rail-seating surfaces.
30. 6. A rail joint for canted rails including in combination with the rails, splice bars having rail supporting bases provided with
- complemental laterally inclined rail seating surfaces.
7. A rail joint for canted rails including in combination with the rails, opposite joint bars having rail supporting bases provided with complemental laterally inclined rail seating surfaces, and having upstanding web portions whose vertical axes are at right angles to said rail seating surfaces.
8. A rail joint for canted rails including in combination with the rails, opposite joint bars having rail supporting bases having substantially horizontal tie engaging surfaces and rail supporting surfaces inclined laterally.
9. A rail joint for canted rails, including in combination with the rails, opposite splice bars having rail supporting base members of tapering thickness, the base member of one bar diminishing in thickness toward the center of the rail, and the base member of the other increasing in thickness toward the center of the rail.

In testimony whereof I hereunto affix my signature in the presence of two witnesses. 55

WILLIAM P. THOMSON.
